UNITED STATES PATENT OFFICE.

ALBERT F. FIFIELD, OF ELIZABETH, NEW JERSEY, ASSIGNOR TO THE SINGER MANUFACTURING COMPANY, A CORPORATION OF NEW JERSEY.

THREAD-CUTTING MECHANISM FOR SEWING-MACHINES.

1,162,998.

Specification of Letters Patent.

Patented Dec. 7, 1915.

Application filed April 8, 1914. Serial No. 830,344.

To all whom it may concern:

Be it known that I, ALBERT F. FIFIELD, a citizen of the United States, residing at Elizabeth, in the county of Union and State of New Jersey, have invented certain new and useful Improvements in Thread-Cutting Mechanisms for Sewing-Machines, of which the following is a specification, reference being had therein to the accompanying drawings:

This invention has for its object to provide a simple and effective device for severing the stitching thread or threads at the end of a straightaway seam of a length controllable by the operator.

In its preferred form, the improvement comprises a sewing machine provided with stitch-forming mechanism including a needle and a co-operating shuttle acting in conjunction with suitable feeding mechanism to produce straightaway stitching, combined with thread-cutting mechanism arranged below the throat-plate and adapted to sever one or both of the stitching threads.

The machine is provided with a stop-motion controlled in its action by a starting lever and has a controlling cam performing a single-rotation to a plurality of stitch-forming cycles.

The constantly moving controlling cam imparts reciprocatory movements to a follower adapted to be connected by a spring-actuated coupling element with one arm of a vibratory lever for imparting the initial or thread-positioning stages of movement of the thread-cutting elements. The cam is provided with means for retracting the coupling element which is normally retained in an inoperative position by means of a spring detent operatively connected with the starting lever and held by the latter disengaged from the coupling element during the running of the machine. The coupling element has connected therewith a shifting carrier for a tripping pin normally disposed in operative relation with one arm of a detent-lever whose other arm detains a vibratory stop-lever of the stop-motion in running position. The tripping pin is periodically acted upon by a tripping point upon the controlling cam, but when the starting lever is in running position the tripping pin remains shifted out of operative relation with

the stop-motion detent-lever, and acts idly without effect upon the stop-motion.

The final or thread-severing stage of movement of the cutting elements is produced in a manner well-known by a connection of the stop-lever with the cutting mechanism, such movement being effected by the overthrow of the stop-lever under the momentum of the machine while coming to rest.

In the accompanying drawings, Figure 1 is a perspective view of a sewing machine provided with the present improvement, taken from the rear side, and showing certain parts in section. Fig. 2 is a perspective view, taken from the opposite side, of the thread-cutter and stop-motion controlling devices, and showing these parts in different relation from that of Fig. 1. Fig. 3 is a perspective view showing detached the cam-follower lever, the cutter-actuating lever and the coupling element for connecting the same together.

The machine is shown constructed with the usual bed-plate 1 and bracket-arm 2 in the upper-member of which is journaled the main-shaft 3 carrying upon its rearward end the fast and loose pulleys 4 and 5. In the head of the bracket-arm is journaled the usual rectilinearly reciprocating needle-bar 6 having the usual operative connection with the main-shaft 3 (not shown) and carrying the eye-pointed needle 7 co-operating in the production of stitches with the oscillating shuttle 8 in practice mounted in a suitable raceway and deriving its operative movements from the shuttle-driver 9 upon the rock-shaft 10 disposed beneath the bed-plate and having the usual connection with the main-shaft.

The feeding mechanism is of well-known form, comprising an eccentric upon the main-shaft embraced by the yoked upper end of the link-bar 11 connected with an arm of the feed rock-shaft 12 disposed beneath the bed-plate and provided with the spaced upright arms 13 to which is pivotally attached the feed-bar 14 carrying the feed-dog 15 extending through a suitable aperture in the throat-plate 16. In general construction and mode of operation the thread-cutting mechanism and stop-motion are substantially as shown and described in the United States Patent to J. J. Sullivan No. 777,564, of December 13, 1904.

The main shaft carries the usual stopping cam engaged by the spring-pressed plunger-bar carried by the stop-lever 17 pivotally mounted in the oscillatory bearing plug 18. The stop-lever 17 is pressed normally backward into stopping position by means of the spring 19 and its lateral motion under the momentum of the moving parts is resisted by the thrust-pin 20 with its cushioning spring 21. The stop-lever 17 carries at its upper end the belt-slipping fork 22 and is provided also in its rearward face with the notch 17' normally entered by the wedge-shaped extremity of the detent-lever 23 mounted upon the fulcrum stud-screw 24 and pressed normally into operative relation with the stop-lever by means of the spring 25. The rearwardly projecting part 26 of the bracket-arm is provided on its rearward edge with a flat seat having the projecting stud-screws 27 entering the elongated apertures 28 in the slide-bar 29 provided with the transverse socket 30 in which is fitted the endwise movable tripping plug 31 provided with the lateral pin 32 passing through a suitable slot in the socket and pressed normally backward in said socket by means of a spring 33 upon the bar 29. One end of the pin or plug 31 is adapted for engagement with the forwardly extending arm of the detent-lever 23, while the opposite end lies in the normal path of movement of one of the inclined tripping plates 34 secured upon the inner face of the rotary controlling cam 35. The hub 36 of this cam is fitted upon the hub 37 of the peripherally toothed wheel 38 which is mounted upon the fulcrum stud 39 fixed in the bracket-arm. The cam 35 and toothed wheel 38 are secured together to rotate in unison by means of the bolt 35. The gear-wheel 38 meshes with a pinion 40 fixed upon one end of the short shaft 41 having upon its opposite end the bevel-wheel 42 meshing with the bevel pinion 43 which is fixed upon the main-shaft 3 and communicates to the cam-wheel 35 through the described connections one rotation for a plurality of rotations of the main-shaft and consequently a plurality of stitch-forming cycles.

The cam 35 has in its rearward face the cam-groove 44 entered by a follower in the form of a roller-stud 45 carried by the vibratory lever 46 having the divided hub 47, 47' which is loosely journaled upon the hub 48 of the cutter-actuating vibratory lever formed with the depending arm 49 and the upwardly extending arm 50. The hub 48 is journaled upon the fulcrum stud-screw 51 tapped into the boss 52 of the bracket-arm.

The lever-arm 50 is reduced in width above its hub portion and provided near the latter with a transversely apertured boss 53 embraced by the similarly apertured lateral

members 54 of the channeled coupling lever 55 adapted to receive the outer portion of the lever 50 within its channel, as represented in Fig. 2. The coupling lever 55 is pivotally sustained by the apertured boss 53 of the rock-lever arm 50 by means of the pivotal pin 56.

Secured upon the rearward face of the coupling lever 55 by means of screws 57 is the cross member 58 of a lateral arm 59 carrying the stud-screw 60 and having secured thereto by means of the fastening screw 61 the lateral portion of a bent wire passing through the arm 59 and extending therefrom laterally in the form of a pin 62 which enters an aperture in the lower portion of the slide-bar 29 and serves to connect the slide-bar with the coupling lever 55.

As shown and described more fully in the said Patent No. 777,564, the throat-plate has mounted therein the fulcrum-pin 63 for the oscillatory carrier 64 which sustains the upper and lower thread-cutting knives 65 and 66, respectively. The carrier 64 is operatively connected with a lateral arm 67 of the reciprocating bar 68 mounted in suitable guides beneath the bed-plate and provided with a lateral fork 69 entered by the tapered lower arm 49 of the cutter-actuating rock-lever. The bar 68 is normally drawn forwardly by means of the spring 70 having its rearward end attached to said bar and its forward end secured to one of the bearing straps 71 by which it is supported beneath the bed-plate. By the action of the spring 70 the forward edge of the arm 49 is normally maintained in contact with the adjustable point of the stop-screw 72 mounted in the bracket 73 upon the bed-plate. At its rearward end the bar 68 has a depending stud 74 which enters the forked extremity of the lateral arm 75 of a bellcrank suitably fulcrumed beneath the bed-plate and provided with the rearwardly extending arm 76 carrying the spring-pressed pin 77 adapted to enter the slot 78 in the lower end of the stop-lever 17.

The actuating cam-groove 44 in the controlling cam is so shaped that, when the arms 46 and 50 are connected by means of the coupling lever 55, the cutter-blades 65 and 66 advance by plural-stage movements to successively engage with their blunt-edged forward extremities first the shuttle-thread and then a loop of needle-thread distended by the shuttle, at which latter stage a clearance space 44' is presented to the roller-stud 45. The pin 77 having entered the slot 78 of the stop-lever 17, the lateral throw of the latter in effecting the final stoppage of the machine causes the final actuation of the cutter-blades to bring their cutting edges into operative relation with the threads for severing the same.

Pivotedly mounted by means of the screw 133

pin 79 between the spaced ears of the bracket 80 is the hub 81 of the starting lever formed with the lateral apertured arm 82 and depending arm 83 normally resting upon the 25 rearward edge of the stop-lever 17. An adjacent depending arm 84 has secured to the side face thereof by means of the screw 85 the foot 86 of a forwardly extending rigid arm 87 having attached to its apertured outer end the upper extremity of a 10 spring 88 connected at its opposite end to the pin 89 by means of which the starting lever is normally maintained in its upper position in which the arm 87 yieldingly rests 15 upon the stop-pin 90 projecting from the bracket-arm.

Projecting from the base of the arm 87 is the stud 91 having in its outer end the guide-screw 92 passing through the slot 93 20 in the rearward end of the link 94 whose opposite end is pivotally connected at 95 with the upper end of the latch or detent-lever 96 formed in its forward edge with the notch 97 to afford a latch shoulder and 25 pivotally mounted at its lower end upon the stud-screw 98. The lever 96 has adjacent its fulcrum-point the rearwardly extending hook 99 to which is connected one end of the spring 100 having its opposite end attached 30 to the stud-screw 60 of the coupling lever-arm 59. The spring 100 serves to normally draw down the coupling lever-arm 59 and thereby effect the coupling of the arms 46 and 50 when in register or overlapping relation, while said spring also acts to yieldingly press the latch-lever 96 into operative 35 relation with the arm 59 for prevention of such coupling action.

The upper or outer extremity of the coupling lever 55 has upon one of its faces a lateral wing 55' within inclined operative edge normally lying within the path of movement of each of the lateral cam projections 101 upon the plates 102 adjustably secured upon the periphery of the cam-wheel 35 by means of screws 103. By means of these cam projections, the disconnection of the vibratory levers 46 and 50 is insured in each semi-rotation of the controlling cam, 45 and such disconnection is maintained so long as the starting lever 82 83 is in running position with the lateral arm depressed, so as to permit the latch-lever 96 to snap into operative engagement with the coupling lever-arm 59 to maintain the arm 55 retracted from engagement with the lever 46, as represented in Fig. 1.

When the machine is at rest, the upper portion of the stop-lever 17 is thrown backwardly with its plunger-bar in engagement with the stopping cam, and, as represented in Fig. 2, the plunger-pin 31 is in its lower operative relation with the detent-lever 33 and the coupling lever 55 is in coupling relation with the vibratory levers 46 and 50.

To start a seam, the lateral arm 82 of the starting lever is drawn downwardly to running position wherein it is manually held during a stitching period, thereby forcing the stop-lever 17 into running position 70 wherein it is engaged and detained by means of the detent-lever 23.

The forward movement of the starting-lever arm 84 permits the advance of the link 94 under the action of the spring 100 to cause the detent-lever 96 to rest upon the side face of the coupling lever-arm 59. The succeeding engagement of the wing 55' by one of the cam projections 101 causes the disengagement of the coupling lever 55 from 80 the lever 46 and the consequent rise of the lateral arm 59 which is detained in such retracted position by engagement of the detent-lever 96, the upward movement of the arm 59 being communicated by the pin 62 85 to the slide-bar 29 and hence to the plunger-pin 31 which assumes inoperative position above the stop-motion detent-lever 23, as represented in Fig. 1.

As the actuating lever 46 performs its 90 vibratory movements under the action of the cam into and out of register with the coupling lever 55, the latter continues in its retracted position under the influence of the latch-lever 96, so that no thread-cutting action is permitted, while the elevation of the plunger-pin 31 above the detent-lever 23 permits its idle endwise movement under the periodical action of the stop-motion tripping points 34 which are duplicated, as are 95 other operative parts of the controlling cam 35, as represented in Fig. 1. It will be observed that the holding force applied to the starting lever-arm 82 by the operator need be only sufficient to counter-balance the impulse of the spring 88, the detent-lever 23 being maintained in operative engagement with the stop-lever 17 during substantially the entire running period of the machine so as to sustain the impulse of the stop-lever 100 spring 19.

When the starting lever is released to permit the machine to come to rest, it rises under the impulse of the spring 88 upon the arm 87, thereby drawing backwardly the 115 link 94 and disengaging the detent-lever 96 from the coupling lever arm 59 so as to permit the coupling lever to assume coupling relation with the vibratory actuating lever 46 under the action of the spring 100 as soon as the levers 46 and 50 come into register in the continued movement of the cam 35. The descent of the coupling lever-arm 59 under the action of the spring 100 produces a like movement of the slide-bar 29 connected therewith, and hence of the plunger-pin 31 whose succeeding operative movement under the action of one of the tripping points 34 causes the tripping of the detent-lever 23 to 120 permit the stop-lever 17 to perform its normal 125 operation.

and stopping action in conjunction with the stopping cam upon the main-shaft of the machine. In practice, the stop-screw 72 for the rock-lever-arm 49 is so adjusted that the arm 50 comes into register with the actuating arm 46 when the latter assumes its extreme rearward position under the influence of the three-step cam-groove 44, so that coupling relation is established in such extreme retracted position of the parts. As the cam 35 continues its rotation, it imparts to the outer-carrier 64, through the described connections, and hence to the two cutter-blades 65 and 66, two-stage advance movements one of which brings the cutter-blade 66 into positioning engagement with the lower or shuttle-thread and the other brings the cutter-blade 65 into the needle-thread loop distended by the shuttle and subsequently deposited thereon, at the completion of which operation the follower-stud 45 is within one of the clearance-spaces 44 of the cam-groove. As the machine comes to rest the overthrow of the stop-lever 17 in opposition to the cushioning action of the spring 21 causes the final operative impulse of the cutting blades to sever the respective threads, in a manner well-known.

As will be observed, in the present embodiment of the improvements, the thread-cutting elements are disposed beneath the throat-plate and have a range of movement wholly at the lower side of the work; and the timing of their action is such as to sever the thread at a predetermined stage of the stitch-forming cycle in which the stop-motion acts to arrest the stitch-forming mechanism, the described controlling means under the control of the manually operated starting lever insuring against the repeated actuation of the cutting mechanism in consecutive stitch-forming cycles of the same stitching-period determined by the control of the stop-motion. It will be observed that the reactivation of the starting lever for a succeeding stitching-period does not in itself effect the uncoupling of the levers 46 and 50, but merely sets the mechanism, including the latch-lever 96, in condition for automatic actuation by means including the cam projections 101 of the controlling cam 35.

As shown and described herein, the cutting elements are actuated by connections with both the controlling cam 35 and the stopping cam upon the main-shaft, but it is evident that the type of cutting device employed will determine whether the stopping cam or a special form of cam driven by the main-shaft shall be employed either singly or jointly to produce the operative movements of the cutting elements. While according to the present disclosure cutting elements are employed for severing both the upper and under thread below the work, it is

evident that the character of the stitch-forming mechanism and other conditions will determine the number and location of the cutting elements to be used.

It is evident that the present improvement 70 is susceptible of very material modification in the construction and arrangement of its component parts within the scope of the present invention, and that the type of stitching mechanism and that of the thread-cutting 75 elements and specific actuating means therefor shown and described herein are not essential thereto.

Having thus set forth the nature of the invention, what I claim herein is:—

1. In a sewing machine, the combination with stitch-forming mechanism, of thread-cutting mechanism including a reciprocatory member, actuating means therefor including a constantly active reciprocatory member, manually controlled means for coupling said members for reciprocation in unison, and means for insuring against the repeated actuation of the cutting mechanism in consecutive stitching cycles of the same 90 stitching period.

2. In a sewing machine, the combination with stitch-forming mechanism, of thread-cutting mechanism including a vibratory lever, actuating means therefor including a vibratory lever, manually controlled means for coupling said levers for movement in unison, and means acting independently of said manually controlled means for effecting the uncoupling of said levers. 100

3. In a sewing machine, the combination with a rotary shaft and stitch-forming mechanism operatively connected therewith, of thread-cutting mechanism including a reciprocatory member, actuating means therefor including a rotary cam, a reciprocatory follower therefor and a driving connection between said shaft and cam for imparting to the latter rotations of less frequency than those of said shaft, and 110 manually controlled means including a normally stationary lever operable while the machine is running for effecting the coupling and uncoupling of the reciprocatory member with said follower for movement in 115 unison therewith.

4. In a sewing machine, the combination with stitch-forming mechanism, of thread-cutting mechanism including a cutting element having a range of movement entirely 120 at one side of the work and a reciprocatory member operatively connected therewith, actuating means for said mechanism including a constantly active reciprocatory member, and means including a spring-actuated coupling element and a manually controlled latch therefor for effecting the coupling of said members for reciprocation in unison.

5. In a sewing-machine, the combination 130

- with stitch-forming mechanism, a stop-motion therefor, and a starting lever for operating the stop-motion to start the machine, of a thread-cutting device, actuating 5 means therefor, and means connected with said starting lever independently of the stop-motion for effecting the coupling of the thread-cutting device with its actuating means.
- 10 6. In a sewing machine, the combination with stitch-forming mechanism, and a stop-motion therefor including a spring-pressed stop-lever and a detent therefor, of a thread-cutting device, actuating means therefor, a 15 spring-actuated coupling element for operatively connecting said cutting device with its actuating means, a detent for said coupling element, and manually controlled means for disengaging said detents from the 20 stop-lever and coupling element, respectively.
7. In a sewing machine, the combination with stitch-forming mechanism, and a stop-motion therefor including a spring-pressed stop-lever and a detent therefor, of a thread-cutting device, actuating means therefor, a 25 spring-actuated coupling element for operatively connecting said cutting device with its actuating means, a detent for said coupling element, and means including a manually controlled lever and independent connections between the same and said detents whereby they are disengaged from said 30 stop-lever and coupling element, respectively.
8. In a sewing machine, the combination with a shaft, stitch-forming mechanism connected with and actuated by said shaft, and a thread-cutting device, of a cam permanently connected with said shaft, a reciprocating follower therefor, a reciprocating member connected with said thread-cutting device, a coupling element for connecting said follower and reciprocating member, and 45 manually controlled means for operating said coupling element.
9. In a sewing machine, the combination with a shaft, stitch-forming mechanism, a stop-motion for controlling the operation of said shaft, and a thread-cutting device, of a cam permanently connected with said shaft, a connection between said cam and the thread-cutting device and comprising two independently movable members with a coupling element for connecting them together, and manually controlled means for rendering 50 said stop-motion and coupling element active or inactive in the performance of their respective functions.
- 60 10. In a sewing machine, the combination with a shaft, stitch-forming mechanism, a stop-motion for controlling the operation of said shaft, and a thread-cutting device, of a cam permanently connected with said shaft, a connection between said cam and the thread-cutting device and comprising two independently movable members with a coupling element for connecting them together, and manually controlled means for rendering 55 said stop-motion and coupling element active or inactive in the performance of their respective functions.
11. In a sewing machine, the combination with a shaft, stitch-forming mechanism, a stop-motion comprising a spring-pressed lever for controlling the operation of said shaft, and a thread-cutting device, of a cam permanently connected with said shaft, a connection between said cam and the thread-cutting device and comprising two independently movable members with a coupling element for connecting them together, a detent for said spring-pressed lever of the stop-motion, a tripping element carried by 65 said cam, and manually controlled means for effecting the establishment and interruption of operative relation between said tripping element and detent and between said coupling element and said independently movable members.
12. In a sewing machine, a thread-cutting mechanism comprising a cutting element, levers having a common fulcrum upon which they are independently movable, a cam for 70 operating the one and a connection between the other of said levers and said cutting element, coupling means for connecting said levers for movement in unison, and means for insuring action of said coupling means 75 at a predetermined stage of a stitch-forming cycle.
13. In a sewing machine, the combination with stitch-forming mechanism, and a stop-motion therefor, of thread-cutting mechanism including a reciprocating member, actuating means therefor including a constantly acting reciprocating member, means for coupling said members for reciprocation in unison, and manually controlled means 80 for actuating said stop-motion and coupling means in the same stitch-forming cycle.
- In testimony whereof, I have signed my name to this specification, in the presence of two subscribing witnesses.

ALBERT F. FIFIELD.
